UNITED STATES PATENT OFFICE.

GEORGE A. WATKINS, OF COLUMBUS, OHIO.

FORM FOR CEMENT CISTERNS.

1,080,187.

Specification of Letters Patent.

Patented Dec. 2, 1913.

Application filed August 2, 1911. Serial No. 641,982.

To all whom it may concern:

Be it known that I, GEORGE A. WATKINS, a citizen of the United States, residing at Columbus, in the county of Franklin and 5 State of Ohio, have invented certain new and useful Improvements in Forms for Cement Cisterns, of which the following is a specification.

My invention relates to a form for cement 10 cisterns and is particularly devised in an endeavor to produce a knock-down form of extreme simplicity combined with rigidity and to attain such result in a manner that will permit of the removal of independent 15 sections constituting the form without in any way decreasing the security of the remaining parts in their proper position.

Further than this, I aim to provide a 20 structure of form comprising a crown made up of independent elements, which are given capability for adjustment within a small range by the provision of a collar member connecting the inner extremities of said 25 crown elements and adjustable by especially provided means. The adjusting means is of peculiar type for the purpose of increasing the security of the collar in its adjusted position.

My invention further resides in the 30 provision of braces for certain of the sections comprising the body portion of the form. It may, also, be noted that these sections are of such a structure, that aside from their 35 independent support when in normal position, they preclude the admission of moisture to any appreciable degree within the form during the molding operation.

The preferred adaptation of my invention is shown in the accompanying drawings, in which similar characters of reference 40 designate corresponding parts, and in which:

Figure 1 is a top plan view partly broken away of my form in assembled condition, Fig. 45 2 is a side elevation, partly broken away, of the form, Fig. 3 is a detail view of the collar and adjusting rods, Fig. 4 is a detail view in elevation of a section of my 50 form showing the latching mechanism for the independent crown elements, Fig. 5 is

a section taken on line 5—5 of Fig. 4, Fig. 6 is a detail plan view of the upper member of my collar structure, and, Fig. 7 is a detail plan view of the complementary member of my collar structure.

55

My concrete form is shown in the drawings as comprised of cylindrical sections 1, 2, 3 and 4 which are each preferably formed from a number of segmental pieces of thin flexible metal having their ends over-lapping as at 5 and joined by hinge members 6 and pintles 7.

60

The bases of the members 2, 3 and 4 are preferably formed with concentric annular flanges 8 which are adapted to fit over the 65 upper edges of the sections upon which they are superimposed. Coacting with these annular flanges are pivoted button members 9 for normally maintaining the sections in place. This structure of joint between the 70 sections is peculiarly adapted for excluding moisture from the interior of the form during the molding operation. It is further apparent that the flange becomes embedded in the concrete surrounding the 75 same and rests upon the ridge formed thereby. Owing to this result, it becomes possible to withdraw any section or portion of section without in any way jeopardizing the 80 stability of the remainder of the form. Inasmuch as the section 1 is subjected to the full weight of the form and concrete, it is desirable to provide the same with bracing members and for practical convenience, reliability and strength, I find it most desirable to utilize such braces as are shown at 85 10 which are connected to brackets 11 and are preferably so disposed as to bisect the circumference of such section at short intervals.

90

The body portion of the form is preferably surmounted by a crown member comprised of a plurality of radially disposed elements of fan shape. These elements are designated 12, 12^a and 12^b and extend uniformly to a point just without the cylindrical body portion forming an eave in connection therewith. The inner ends of the elements 12, 12^a and 12^b are preferably connected as best shown in Fig. 3, to a com- 100

pound collar member comprised of a unit 13 having radial slots 14 therein and a complementary unit 15 surmounting such unit 13. The unit 13 is L-shaped in cross section 5 and the slots are adapted to receive flanges 16 of L-shape formed upon the elements 12 and 12^a, these elements being identical in form, with the exception of the element 12^a, which is provided with a flange upon either 10 edge and 12^b which has no flange. It will be understood that this peculiar formation of the element 12^a in comparison with the elements 12, is because this element 12^a forms a key element for the elements 12. 15 In other words, the elements 12 overlap each other, but the element 12^a is overlapped upon both edges. The provision of the flanges or angle irons 16 upon the edges of the elements comprising the crown member, is 20 partly for the purpose of positively locating the elements because the said flanges or angle irons fit within the slots 14 and partially to serve as a rigid series of braces for the crown. Inasmuch as the element 12^b, which 25 overlaps the element 12^a along one edge and one of the elements 12 along its other edge, cannot be provided with a brace, because of such overlapping effect, the element 12^a is provided with a brace upon either edge. In 30 normal operation, the collar unit 15, which is of L-form in cross section, is forced downwardly upon the inner ends of the elements 12, 12^a and 12^b by means of nuts 17 and 18 upon the threaded extensions 19 of the fork 35 members 20. This produces a rigid gripping action upon the inner ends of the said elements and holds them in a practically perfect alignment. The fork members 20 are adapted to be extended downwardly and 40 attached to brackets 21 preferably carried by the inner periphery of the section 3. With reference to Fig. 3, it will be noted that these brackets 21 have their horizontal arms 22 each coacting with two nuts 20^a on 45 the lower threaded extremities of the fork members 20 and disposed upon opposite sides of such legs 22, which permits a slight vertical adjustment of the fork members or a slight tilting thereof to regulate, with 50 more exactness, the position of the collars. The outer ends of the elements 12, 12^a and 12^b are preferably provided upon their under surfaces and within the cylindrical body, with keeper members 23 for the reception 55 of pivoted latches 24 of substantially L-shape and capable of swinging into position to lock each element to the cylindrical body portion.

In operation, it will be understood that it 60 is desirable to form the base of the cistern initially, and to then place the section 1 in position and brace the same by the brace members 10. After this, the section 2 is placed in position upon the section 1 and is

assembled by means of the pintles 7 and 65 hinge members 6. When the portions of this section are assembled upon the section 1, the section 2 is preferably locked in position by the pivoted buttons 9. The remaining sections are then applied in a substantially identical manner and the crown elements are placed in position with their inner ends clamped in the compound collar and their outer ends resting upon the upper edges of the formed cylindrical body. Then, 70 the latches 24 are moved into position beneath the keepers 23 and the forked members 20 are attached to the brackets 21 and adjusted for properly positioning the collar. After this, the cylindrical collar member 26 is placed loosely upon the collar 15. 75 It will be noted that this collar may be formed in segments as shown at 27. It will also be noted that I preferably utilize an external collar member 28 for forming the collar of the molded cistern more perfectly annular. In dismantling the device, it is only necessary to release any button 9 and the pintles 7 and to withdraw any section. The remaining sections will be positively maintained in place, inasmuch as they rest upon the ridges formed by their base flanges. To dismantle the crown member, it is desirable to withdraw the element 12^a first. This is 80 done by first swinging the pivoted latch 24 85 out of engagement with its keeper 23, loosening the compound collar and moving the element 12^a inwardly until its outer extremity clears the upper edge of the cylindrical body. The element is then swung 90 downwardly and removed. The release of the remaining crown elements is effected in a substantially similar manner.

It will be apparent that I have provided a form for molding concrete cisterns, which 105 may be readily dismantled, inasmuch as it is possible to remove any element without rendering the remainder of the structure liable to collapse. It is further apparent that I have provided a concrete form where- 110 in the collar may be adjusted to properly elevate or lower the collar or to slightly rotate the collar by an adjustment of one of the legs of a forked member.

What I claim, is—

1. A form for cement cisterns comprising a body, a plurality of crown pieces, a collar embracing said crown pieces at their inner ends, and forked adjusting rods between said collar and said body.

2. A form for cement cisterns comprising a body, a plurality of crown pieces, and a collar element comprising multiple pieces mounted in superposed relation with each other for supporting the inner ends of said 125 crown pieces.

3. A form for cement cisterns comprising a body, a plurality of crown pieces, a collar

115

120

125

element for supporting the inner ends of said crown pieces, keeper elements, and pivoted latch elements for co-action with said keepers for supporting said crown pieces at 5 their outer ends.

4. A form for cement cisterns comprising a body, a plurality of crown pieces, a collar element for supporting the inner ends of said crown pieces, keeper elements on the

outer ends of said crown pieces, and pivoted latch elements on said body for coaction with said keepers.

In testimony whereof I affix my signature in presence of two witnesses.

GEORGE A. WATKINS.
